UNITED STATES PATENT OFFICE.

ABRAHAM J. SCHULTZ, OF NEWARK, NEW JERSEY.

BEDSTEAD CORNER LOCK.

Application filed June 23, 1926. Serial No. 117,959.

This invention refers, generally, to improvements in corner locks for bedsteads adapted to securely connect between the head and foot members thereof the longitudinal 5 side or stretcher bars.

The invention has for its principal object to provide an inexpensive and yet very strong and durable corner lock construction, whereby a rigid and secure connection of the 10 longitudinal side or stretcher bars between the head and foot frames of a bed may be attained.

The invention has for a further object to provide a novel corner lock structure, the 15 parts of which may be produced by metal stampings subject to a novel assembled relation respectively to the corner bedposts and the ends of the side or stretcher bars, and further subject, when thus assembled to 20 a cooperative union adapted to produce a very rigid, secure and strong coupled relation of bedpost and side or stretcher bar free from loose play, shearing or other undesired displacement.

25 Other objects of this invention, not at this time more particularly enumerated, will be clearly understood from the following detailed description of the same.

The invention is clearly illustrated in the 30 accompanying drawings, in which:—

Figure 1 is a side elevation of a bedpost and side or stretcher bar end respectively provided with the cooperating corner lock elements made according to this invention, 35 and shown in disconnected relation; Figure 2 is a similar view showing the manner of bringing the cooperative corner lock elements together; Figure 3 is a similar view showing the complete final cooperative union 40 of said corner lock elements; Figure 4 is a plan view of the parts in operative united relation; Figure 5 is a detail transverse section, taken on line 5—5 in Figure 3; Figure 6 is a detail longitudinal section, taken 45 on line 6—6 in Figure 4; and Figure 7 is a detail transverse section, taken on line 7—7 in said Figure 3.

Similar characters of reference are employed in all of the hereinabove described 50 views, to indicate corresponding parts.

Referring now to said drawings, the reference character 8 indicates a bedpost of either the head or foot frame of the bedstead as the case may be, and the reference 55 character 9 indicates a side or stretcher bar made of angle iron, which is adapted to be

coupled to and to extend between bedposts respectively at the head and foot of the bedstead.

Secured to the bedpost 8 by rivets 10, or any other convenient form of fastening 60 means is a socket element. This socket element is stamped from sheet metal of suitable gauge, and is so formed as to provide a base-portion 11 to abut or engage against the bedpost 8, and which, if the latter is of cylindrical conformation, is transversely arcuate or curved to fit the bedpost of such form. 65 Integrally formed with said base-portion 11, so as to extend outwardly from one vertical side of the same, is a socket plate 12, which is cut away in its upper end portion to provide an upwardly open downwardly extending socket 13, bounded on its outer side by a slightly tapered finger 14. The interior 70 angle at the juncture of said base-portion 11 and socket plate 12 is formed to provide a seat 15, the function of which will presently appear.

Secured to each end of the side or stretcher 75 bar 9 is an abutment plate 16 adapted to be stamped from sheet metal of suitable gauge. Said abutment plate 16 is registered against the inner face of the vertical flange *a* of said side bar 9. Said abutment plate is integrally provided at its outer end with a vertical outwardly off-set butment or tenon 17, the free or edge portion of which is disposed to lie in the plane of said vertical flange *a* of said side bar 9, and so as to project outwardly endwise from the latter; the juncture of said offset butment or tenon 17 with the outer side of said abutment plate 16 provides a shoulder 18 against which the end of the side bar 9 is stopped or registered. 80 Said abutment plate 16 is further integrally provided at its upper edge portion with a horizontal inwardly off-set bearing or butress flange 19 which is adapted to abut the underside of the horizontal flange *b* of said side bar 9. Said abutment plate 16, when the same is formed, is provided with rivet receiving openings accurately disposed in desired predetermined positions, so that when the abutment plate 16 is properly positioned relative to the side bar 9, the same 85 serves as a template for positioning and producing corresponding rivet openings in the vertical flange *a* of said side bar 9. This procedure assures a proper corner lock structure in connection with each end of the side bar, whereby an accurate cooperating fit

105

110

with the socket element is always attained, even though there may be some slight variations in the lengths of the side bars 9.

When the registering rivet receiving openings are provided in the abutment plate 16 and side bar 9, these parts are accurately secured together in proper assembled relation by means of fastening rivets 20 and 21 which are passed therethrough. One of said rivets, as 20, is provided at its outer end, which projects from the outer face of the vertical flange *a* of said side bar 9, with a headed coupling stud 22 the shank 23 of which is receivable in the socket 13 of said socket plate 12; the other rivet, as 21, is provided at its outer end, which projects from the outer face of the vertical flange *a* of said side bar 9 with a head 24 adapted to provide a stop or brace adapted to cooperate with the outer side of said finger 14 of said socket plate in the manner subsequently referred to.

When assembling an end of the side bar 9 with a bedpost 8, the outer side of the vertical flange *a* of said side bar is positioned to face the inner side of the socket plate 12, and with the shank 23 of the coupling stud 22 alined above the socket 13 of said socket plate, as shown in Figure 1. When the parts are thus disposed the side bar end is moved downwardly to carry the coupling stud into the socket, as shown in Figure 2. In this position the abutment or tenon 17 of the abutment plate 16 enters slidably into the seat 15 of the socket element, while the tapered finger 14 is entered slidably between said coupling stud shank 23 and the stop head 24. When the side bar 9 is thus initially positioned and united through the corner lock devices with the bedpost 8 it is brought to final united relation by driving down the side bar end until the coupling stud shank 23 seats itself in the bottom of the socket 13 of the socket plate 12, and the butment or tenon 17 is fully entered in the seat 15 of the latter, so as to firmly brace the end of said side bar 9 against looseness, play or other displacement, and thus aiding in attaining and maintaining the desired rigid union with and desired square and true alignment of the side bar in its operative extension between the head and foot frames of the bedstead. The function of the bearing or buttress flange 19 of the abutment 16 is two-fold; first it serves to squarely and truly aline the abutment plate 16 with the side bar 9, and assures the desired vertical alignment of the butment or tenon 17 relative to the seat 15 of the socket element, and, second, it braces and supports the side bars 9 against vertical displacement or shifting relative to the abutment plate 16 which would tend to produce a shearing action on the rivets 20 and 21. In forcing the coupling stud 22 tightly down into the socket 13 of the socket plate 12, any tendency to spread or

bend the finger 14, which bounds the outer side of said socket 13, is obviated by reason of the stopping or bracing effect which the head 24 of the rivet 21 offers by its engagement with the outer edge of said finger 14, as shown in Figure 3. It will thus be apparent that a frictional gripped relation of the socket plate relative to the coupling stud is effected, which counteracts any tendency of the engaged corner lock elements to loosen or become relatively displaced.

From the above description it will be quite apparent that the present invention produces a very simple construction of corner lock structure for bedsteads, which comprises a minimum number of parts, which, however, by reason of the novel structural features adapted to mutual cooperation, as above described, produces an exceedingly rigid union between the bedposts and side bars which is free from all tendency to looseness or play, and which therefore maintains said parts of the bedstead in true and square coupled relation one to another.

I am aware that some changes may be made in the arrangements and combinations of the various devices and parts, as well as in the details of the construction of the same, without departing from the scope of this invention as set forth in the foregoing specification, and as defined in the appended claims. Hence, I do not limit my invention to the exact arrangements and combinations of the said devices and parts as described in said specification, nor do I confine myself to the exact details of the construction of parts as illustrated in the accompanying drawings.

I claim:

1. A corner lock structure for connection between a bedpost and angle-iron side bar of a bedstead, comprising an integral socket element consisting of a base portion to abut and be secured to said bedpost and a socket plate extending outwardly from one side of said base portion, said socket plate having an upwardly open downwardly extending socket in the body thereof bounded on its outer side by a finger-like member, said socket member having a vertically extending seat located in the interior angle of juncture of said base portion and socket plate; and an abutment plate registered against the inner side of the vertical flange of said side bar, laterally spaced rivets extending through said abutment plate and side bar to secure the same together, one of said rivets terminating at the outer face of said side bar in a headed coupling stud and the other of said rivets terminating at the outer face of said side bar in a stop head, said abutment plate having at its outer end a vertical off-set tenon projecting endwise beyond and lying in the vertical plane of said side bar with its rearward shoulder

abutting the end of the latter, said tenon slidably fitting into said vertical seat of said socket element when said headed coupling stud is entered in said socket of said socket plate, and the outer edge of said finger-like member abutting said stop head so as to be held against distortion when said headed coupling stud is entered in said socket of said socket plate.

10 2. A corner lock structure for connection between a bedpost and angle-iron side bar of a bedstead, comprising an integral socket element consisting of a base portion to abut and be secured to said bedpost and a socket plate extending outwardly from one side of said base portion, said socket plate having an upwardly open downwardly extending socket in the body thereof bounded on its outer side by a finger-like member, said
20 socket member having a vertically extending seat located in the interior angle of juncture of said base portion and socket plate; and an abutment plate registered against the inner side of the vertical flange of said side bar, laterally spaced rivets extending through said abutment plate and side bar to secure the same together, one of said rivets terminating at the outer face of said side bar in a headed coupling stud and the
25 other of said rivets terminating at the outer face of said side bar in a stop head, said abutment plate having at its outer end a vertical off-set tenon projecting endwise beyond and lying in the vertical plane of said side bar with its rearward shoulder abutting the end of the latter, said tenon slidably fitting into said vertical seat of said socket element when said headed coupling stud is entered in said socket of said socket plate,
30 the outer edge of said finger-like member abutting said stop head so as to be held against distortion when said headed coupling stud is entered in said socket of said socket plate, and said abutment plate having an inwardly off-set horizontal buttress flange to engage the under side of the horizontal flange of said side bar.

3. A corner lock structure for connection between a bedpost and side bar of a bedstead, comprising an integral socket element consisting of a base portion to abut and be secured to said bedpost and a socket plate extending outwardly from one side of said

base portion, said socket element having a vertically extending seat located in the interior angle of juncture of said base portion and socket plate; and an abutment plate secured to an end of said side bar, said abutment plate having at its outer end a vertical off-set tenon projecting endwise beyond and lying in the vertical plane of said side bar, coupling means connected with said side bar receivable by said socket plate, said tenon being receivable in said vertical seat of said socket element when said side bar coupling means is entered in said socket plate, and said abutment plate having an inwardly offset horizontal buttress flange to engage the under side of the horizontal flange of said side bar. 55 60 65 70

4. A corner lock structure for connection between a bedpost and an angle-iron side bar of a bedstead, comprising an integral socket element consisting of a base portion to abut and be secured to said bedpost and a socket plate extending outwardly from one side of said base portion, said socket plate having an upwardly open downwardly extending socket in the body thereof, said socket element having a vertically extending seat located in the interior angle of junction of said base portion and socket plate; and an abutment plate registered against the inner side of the vertical flange of said side bar, fastening means to secure said abutment plate and side bar together, said abutment plate having at its outer end a vertical off-set tenon projecting endwise beyond and lying in the vertical plane of said side bar with its rearward shoulder abutting the end of the latter, a headed coupling stud anchored in said abutment plate and side bar to project outwardly from the outer face of the vertical flange of the latter, said headed coupling stud being receivable in the socket of said socket plate, said tenon being receivable in said vertical seat of said socket element when said coupling stud is entered in said socket, and said abutment plate having an inwardly off-set horizontal buttress flange to engage the under side of the horizontal flange of said side bar.

In testimony, that I claim the invention set forth above I have hereunto set my hand this 17th day of June, 1926.

ABRAHAM J. SCHULTZ.
